UNITED STATES PATENT OFFICE

NORMAN H. SAUNDERS, OF HOMEWOOD, ILLINOIS, ASSIGNOR TO RESERVE HOLDING COMPANY, OF CHICAGO, ILLINOIS, A CORPORATION OF DELAWARE

TELEPHONE SYSTEM

Application filed December 10, 1926. Serial No. 153,791.

The present invention relates to telephone systems in general, but is concerned more particularly with the production of a new and improved apparatus for use in telephone systems for supplying service to networks of small telephone exchanges, although many of the new features are not confined thereto.

One feature of the invention has to do with the production of an arrangement for freeing the central office equipment in an automatic exchange when one subscriber on a local battery party line operates his hand generator to signal another subscriber on the same line.

Other features of the invention have to do with the production of new and improved circuits for connector switches for use in extending connections to party lines of the local-battery simplex-dialing type.

Another feature of the invention is concerned with the provision of a new and improved code-generating device for generating the codes necessary to signal the various party-line subscribers to which connections are extended.

Another feature is directed to the provision of a new and improved trunk circuit for use on a trunk line seized by an automatic selector switch and extending to an operator's position. The trunk circuit automatically projects ringing current out over the trunk line to signal the distant operator and cuts off the ringing current when the operator responds.

The foregoing and other features of the invention may be understood best from a further perusal of the specification in connection with the accompanying drawings comprising Figs. 1-9.

Referring now to the drawings, Figs. 1-7 show by means of the usual circuit diagrams a sufficient amount of apparatus in a telephone system embodying the features of the invention to enable the invention to be understood; Fig. 8 is a trunking diagram which shows a telephone net work comprising four exchanges interconnected by trunk lines; and Fig. 9 shows how Figs. 1-7 should be assembled together.

Considering Fig. 8 in detail, the four exchanges shown are A, B, C, and D. Exchanges A and B are automatic exchanges and each has an ultimate capacity approaching a thousand lines, there being a single order of selectors in each office. The exchange C is a manual exchange of the common-battery type, and two way trunk lines are provided connecting this exchange with each of the other three exchanges. And exchange D is an automatic exchange having a capacity approaching 100 lines, this exchange being provided with connectors only.

It is assumed that exchanges A and B are located relatively close to one another, and that telephone service between these two exchanges is charged for at the same rate as telephone service local to either exchange, there being no extra charge for inter-exchange trunking. It is assumed that exchanges C and D are more or less remotely situated from exchanges A and B and from each other, and that there is an extra charge for service between either of the exchanges C and D and any other exchange. And it is assumed that exchange C is of relatively small size and that the same operator handles calls local to the exchange C and also calls involving the exchange C either as a switching point or as an originating point or terminating point for inter-exchange connections.

Upon reference to exchange A, it will be noted that the line of the telephone T1 terminates at the exchange in the lineswitch LS1 and also in the bank of the connector C1. The selector S1 is one of a number of selectors for handling calls originated by the lines such as the line of substation T1. The bank of the selector S1 is multiplied with the banks of the incoming selectors S2 and S3. These selectors have access on the fifth level to a group of connectors of which the connector C2 is one, and they have access on the sixth level to a group of connectors represented by the connector C1. It is assumed that the line of substation T1 is accessible through the twenty-first set of contacts in the bank of connector C1, being line number 621. Referring to exchange B, it will be noted

that the layout of this exchange is the same as that of exchange A, the selector S6 being a local selector, and selectors S4 and S5 being incoming selectors. Connector C3 is reached from the fifth level of the selectors, and connector C4 is reached from the sixth level. The line of substation T2 is assumed to be reached through the first set of contacts in the second level of the connector C4, being line number 621.

Regarding connections between exchanges A and B, it will be noted that there is a two-way trunk line TL3 extending between the repeaters R1 and R2. This trunk line is one of a group provided for extending connections between the two exchanges. This trunk line may be seized at the A-exchange when a selector in the A-exchange is operated to the third level, the repeater R1 being interposed to repeat the dialing impulses and to provide a holding circuit for the selector and lineswitch involved in the connection. In making a call from exchange A to exchange B, the subscriber dials the same number that would be dialed by a subscriber in exchange B to obtain the same connection, except that the subscriber in exchange A prefixes the digit 3 to operate a selector in exchange A to extend connections to an incoming selector in exchange B. In a similar way, calls originated in exchange B and intended for lines terminating in exchange A are handled through a trunk line and an incoming selector such as the trunk line TL3 and the selector S3.

It will be noted that the trunk line TL1 extends between the trunk circuit TC1 in exchange A and the jack J2 in exchange B. This trunk line is a two way trunk line, and the selector S2 in exchange A may be operated over this trunk line when the operator in exchange C makes connection through the jack J2. The trunk line TL1 may be seized by a selector in exchange A through the fourth level, whereupon the trunk circuit TC1 applies ringing current to the trunk line to signal the operator in exchange C. Similarly, the trunk line TL2 is a two-way trunk line connecting exchanges C and B, terminating at the exchange C in the jack J4 and passing through the trunk circuit TC2 in exchange B to the fourth level of the selector bank and to selector S5.

The trunk line TL4 extending between exchanges C and D terminates at exchange C in the jack J3, and, when it is seized through this jack, the line switch LS3 in exchange D is operated to extend the connection to an idle connector, such as the connector C5. When this trunk line is seized in exchange D by a connector, ringing current is projected out over the trunk line by the connector to signal the operator at exchange C.

Referring now to Figs. 1-3, it will be noted that these drawings show the circuits of the

equipment necessary to set up the connections between the telephone substation T1 of exchange A and substation T2 of exchange B. This equipment comprises the lineswitch LS1 and the selector S1, Fig. 1, the repeater R1, trunk line TL3, the repeater R2 and the selector S4, Fig. 2, and the connector C4, Fig. 3. Since the circuits of the selector S4 may be the same as the circuits of the selector S1, the selector S4 has been indicated by a dotted rectangle.

It will be noted that Figs. 1, 2, 5, 6, and 7, show apparatus for extending a connection from the substation T1 of exchange A to the substation T4, of exchange D. This apparatus includes the lineswitch LS1 and the selector S1, Fig. 1, the trunk circuit TC1 and the trunk line TL1, Fig. 2, the trunk circuit TC3 and the cord circuit CC, Fig. 5, the trunk circuit TC5, the trunk line TL4, and the lineswitch LS3, Fig. 6, and the connector C5, Fig. 7.

The apparatus shown in Fig. 4 is the relay device for generating the ringing codes for operating the ringing relays in the connectors to signal the party line subscribers. Although only the code-generating device in exchange B has been shown, it will be understood that a similar device is provided for exchange A and another device is provided for exchange D. It will be noted that the ringing-code conductors shown in Fig. 4 extend to the right-hand edge of the sheet and terminate there in circles labeled 1-10. These circles indicate terminals that are to be connected to the corresponding bank terminals of the various code-selecting switches of the connectors in exchange B, such as the code-selecting switch CS4 of the connector C4, Fig. 3, the bank wires of the switch CS4 being provided with similar circles to indicate the connection between the code-selector bank and the ringing-code conductors. The circles numbered 1'-10' associated with the code-selecting switch CS5 of the connector C5, Fig. 7, indicate that the bank wires of CS5 are connected in the same way to the ringing-code conductors of the associated code-generating device (not shown).

Call from substation T1 to substation T2

A detailed description of the operation of the apparatus shown will now be given. For this purpose it will be assumed first that the subscriber at substation T1, Fig. 1, desires to converse with the subscriber at substation T2, Fig. 3. The called line number is 621, and the station number on the called line is 5. Consequently the number, if called from another telephone in exchange B, is 621-5, the dash being used ahead of the 5 to separate the line number from the stations digit. Since, however, the calling subscriber is in exchange A, he must prefix a 3 to the number, which then becomes 3-621-5. It is as-

sumed that the numbers of subscribers to the two exchanges are listed in separate portions of the directory, and that general instructions are issued to the subscribers to pre-fix the digit 3 when calling from one exchange to the other.

When the subscriber at substation T1, Fig. 1, removes his receiver, the usual receiver and transmitter circuits are completed at the switchhook contacts, and, in addition, a circuit is closed at contacts 108 through the springs 106 of the calling device 105 to the junction of the coils of the bridged ringer 104. When this occurs, current from the exchange battery through the winding of line relay 113 flows through the associated cut-off-relay spring combination through both line conductors 101 and 102 in parallel, being afforded a path to ground at the calling substation through the two windings of the ringer 104 in parallel. Line relay 113 closes a circuit for the pull-down winding 114 through the usual so-called "open-main" conductor 122 to battery. The pull-down winding operates the plunger 117 and the bridge-cut-off armature 116. The bridge-cut-off armature 116 opens the shunt across the talking conductors and disconnects relay 113. Relay 113 is slow releasing and remains operated for an interval. The pull-down armature 117 operates the springs 118-121, extending the line conductors 101 and 102 and the private normal conductor 127 to the corresponding conductors 124, 126, and 125 of selector S1. Line relay 131 of the selector S1 now energizes through the two windings of the impedance 130 and over the two conductors of the calling line in parallel. Line relay 131 closes a circuit for relay 132 and vertical magnet 137, at the same time disconnecting series relay 133 from in shunt of relay 132. Magnet 137 is not operated at this time owing to the relatively high resistance of relay 132. Series relay 133 is of relatively low resistance and magnet 137 will operate when connected in series with relay 133. The circuit of magnet 137 is closed momentarily through relay 133 after the armature of relay 131 has engaged its front contact and before relay 133 has been removed from its shunt of relay 132. This interval, however, is of such a short duration that neither relay 133 nor magnet 137 have time to operate. Relay 132, upon operating, closes a locking circuit for itself at armature 144 including magnet 137, and at armature 145 places ground on release trunk conductor 125. This closes a circuit through the bridge-cut-off and holding winding 115 of the line switch. The current flow through this winding is sufficient to maintain the bridge-cut-off and pull-down armatures operated after relay 113 falls back and opens the circuit through the pull-down winding 114. The advance of the master switch to another idle

trunk takes place responsive to the placing of ground on conductor 125 and is controlled over the branch conductor 123 extending to the master switch bank.

The calling subscriber may now dial the first digit 3 in the desired number, whereupon line relay 131 falls back three times due to the three interruptions produced in its circuit at springs 106 of the calling device 105 upon the return of the calling device to its normal position. It will be noted that off-normal springs 107 of the calling device 105 shunt the coils of the ringer 104 so as to afford a better impulsing circuit for line relay 131 of the selector S1. Each time it falls back, relay 131 places relay 133 in multiple with relay 132. When this occurs the first time, relay 133 operates in series with magnet 137, and magnet 137 operates to raise the wipers of the switch one step. Although the resistance of relay 133 is so low, relatively, that relay 132 will eventually fall back, when shunted by relay 133, it does not have time to do so during dialing. When the armature is again attracted magnet 137 falls back, but the slow-acting relay 133 remains operated until the end of the digit. Magnet 137 is operated two more times, raising the wipers of the switch three steps in all. Upon the operation of relay 133, a circuit is prepared for stepping relay 134. This circuit is completed through the interrupter springs of the rotary magnet 140 and the off-normal contacts 141 as soon as the first step of the switch has been taken. Relay 134 thereupon operates and locks itself to release trunk conductor 125 at armature 147, and at armature 148 prepares a circuit for rotary magnet 140. When relay 133 falls back at the end of the digit, it shifts the circuit of relay 134 to the test wiper 154 preparatory to the usual testing operation, and at the same time completes the circuit of rotary magnet 140. Rotary magnet 140 thereupon operates and advances the wipers 153-155 one step into engagement with the first set of bank contacts in the third level. Near the end of its stroke, magnet 140 opens the circuit of relay 134, whereupon relay 134 falls back and opens the rotary magnet circuit. The rotary magnet falls back and again closes its interrupter contacts.

From this point the operation depends upon whether the trunk line terminating in the first set of bank contacts is busy or idle. If this trunk line is idle, relay 135 operates at this time seizing the trunk. If the trunk line is busy, the ground potential encountered by test wiper 154 on the busy test contact short circuits relay 135 and closes a new circuit through the armature of relay 133, normal, the rotary magnet interrupter contacts, and the off-normal contacts 141 for stepping relay 134. Stepping relay 134 operates again, and again closes the rotary mag-

net circuit, whereupon the wipers are advanced another step.

This alternate operation of relay 134 and magnet 140 continues until an idle trunk line is reached, which trunk line, it will be assumed, is the one comprising conductors 156-158 and extending to the repeater R1, Fig. 2. When this trunk line is reached, no ground potential is encountered by test wiper 154, and relay 135, being no longer short circuited, energizes in a circuit including the grounded release trunk conductor 125, eleventh-rotary-step contacts 142, the rotary-magnet interrupter contacts, off-normal contacts 141, and relay 134. Relay 134 does not operate in this circuit on account of the relatively high resistance of relay 135. Upon operating, relay 135 at armature 151 opens a further point in the test circuit and connects wiper 154 to the grounded release trunk conductor 125, thereby making the seized trunk busy immediately to the other selectors having access to it. At armature 150, relay 135 opens the locking branch of the release relay circuit so as to prevent a further operation of magnet 137 and relay 133 and to prevent a premature release magnet operation, and at armatures 149 and 152 disconnects conductors 124 and 126 from the windings of impedance 130 and line relay 131 and extends them through wipers 153 and 155 to conductors 156 and 158 leading to the repeater R1.

Line relay 201 of the repeater R1 now operates over the calling line and through the two left-hand repeating-coil windings in parallel. At armature 206, relay 201 closes a circuit for release relay 202. Relay 202 operates and closes at armature 208 a circuit for relay 203. At armature 207, relay 202 places ground on release trunk conductor 157, so as to maintain the lineswitch LS1 and the selector S1 operated after the release relay 132 of the selector S1 falls back responsive to being shunted and open-circuited by the line relay 131 when the latter falls back responsive to the operation of switching relay 135.

As a result of the closure of the circuit of relay 203 at armature 208, relay 203, at armatures 209 and 210, disconnects the conductors of the trunk line TL3 from the corresponding conductors leading to the selector S3 and connects them to the right-hand repeating-coil windings. A ground potential is thereby placed on conductors of the trunk line TL3 through the right-hand repeating-coil windings, closing a circuit over the conductors of the trunk line TL3 and through armatures 209' and 210', normal for the line relay (not shown) of the selector S4. This line relay now operates and prepares the selector S4 for operation in the manner described in connection with the selector S1.

When the calling subscriber dials the sec-

ond digit 6 in the desired number, line relay 201 of the repeater R1 falls back six times, and each time it does so it opens the circuit of the line relay of the selector S4. As a result, the selector S4 raises its wipers 212-214 opposite the sixth level and selects an idle trunk line, which trunk line, it will be assumed, is the one comprising conductors 301-303 and extending to the connector C4, Fig. 3. It will be noted that each time relay 201 falls back it opens the circuit of relay 202, but relay 202 remains operated throughout the digit on account of the fact that it is placed in a closed circuit each time before its energizing circuit is opened.

In the connector C4, relay 305 operates responsive to the grounding of conductor 302 by the selector S4 when the latter seizes the trunk line, its circuit including off normal contacts 321. At armature 326, relay 305 prepares a locking circuit for itself, and at armature 328 it connects vertical magnet 325 to the operating conductor 313, at the same time disconnecting rotary magnet 360. Line relay 306 operates over conductors 301 and 303 from the ground potential supplied to the trunk line TL3 through armature 204 of the repeater R1, and it closes a circuit for release relay 307 through vertical magnet 325. Upon operating, release relay 307 places ground on locking conductor 314 at armature 333; grounds release trunk conductor 302 at armature 332; and at armature 334 closes a locking circuit for itself including operating conductor 313, armature 328, and vertical magnet 325.

When the calling subscriber dials the third digit 2 in the desired number, two interruptions are produced in the circuit of line relay 306 of the connector C4 at the line relay 201 of the repeater R1, with the result that relay 306 falls back twice. Each time it falls back, relay 306 shunts relay 307 with the series relay 311, bringing about the operation of vertical magnet 325. By the operation of the vertical magnet, the wipers 357-359 are raised opposite the second level of bank contacts. Series relay 311 energizes upon the first impulse of current and remains energized until the digit is over. At armature 348, relay 311 completes the locking circuit for relay 305 through armature 326. The initial circuit of relay 305 is opened at off-normal contacts 321 as soon as the switch moves off normal. At the end of the vertical movement of the switch, relay 311 falls back and opens the locking circuit of relay 305 at armature 348, whereupon relay 305 falls back and shifts the operating conductor 313 from connection with vertical magnet 325 into connection with rotary magnet 360. At armature 329, relay 305 closes a circuit including off-normal contacts 335 and the start conductor 375 for operating the code 130

generator, Fig. 4, in a manner to be herein-after explained.

When the subscriber dials the next digit 1 in the desired number, one interruption is produced in the circuit of line relay 306 of the connector C4, and this relay falls back momentarily, momentarily shunting relay 307 with series relay 311. This operation transmits an impulse of current through 10 armature 334, operated, and over the operating conductor 313 to rotary magnet 360, through the normally closed contacts controlled by armatures 328 and 355. Rotary magnet 360 responds to this impulse of current and rotates the wipers 357-359 one step into engagement with the terminals of the called line. Relay 311 is energized in series 15 with the rotary magnet. At armature 347, relay 311 disconnects test wiper 358 from the upper winding of relay 312 and connects it 20 instead through armature 350 to busy relay 310, and at armature 348 disconnects ground from armature 344 so as to prevent the premature shunting of relay 311 in case relay 25 310 energizes during the rotary movement due to the passing of wiper 358 over busy test contacts.

The operation taking place at the end of the rotary movement depends upon whether 30 the called line is busy or idle. If the called line is busy, relay 310 is energized through test wiper 358 when the wipers come to rest on the contacts of the called line, and, when relay 311 falls back at the end of the rotary 35 movement, a locking circuit is completed for busy relay 310 from the grounded release-trunk conductor 302 through armature 342, operated, normally closed contacts controlled by armature 347, and armature 350. Relay 311 is shunted at armature 348, normal, through armature 344, so as to prevent it 40 from operating subsequently and interfering with the circuit of busy relay 310 in case the calling subscriber should again turn his calling device before hanging up his receiver. In order to inform the calling subscriber of the busy condition of the line, busy relay 310 at armature 346 connects the busy lead, coming from the busy tone transformer 377, to 45 the lower talking conductor through armature 356. When the calling subscriber hears the tone produced by the busy tone machine, he is expected to hang up his receiver and bring about the release of the operated switches.

Assuming now that the desired line is idle when called, relay 310 is not operated at the 50 end of the rotary movement, and, upon the falling back of relay 311, a circuit is completed for the upper winding of switching relay 312 as follows: from ground by way of the grounded release trunk conductor 302, armature 342, normal, test winding of relay 312, armature 347, test wiper 358, bank contact 362, and the cut-off relay (not shown)

of the lineswitch LS2 to battery. This cut-off relay of the lineswitch LS2 operates over this circuit and disconnects the associated line relay from the conductors of the called line. The cut-off relay of the lineswitch on 70 the called line corresponds to the bridge-cut-off armature 116 of the lineswitch LS1 and the winding 115. The cut-off armature of the called lineswitch is operated, but the pull down armature is not operated owing 75 to the relatively weak pull of the bridge-cut-off winding.

In the connector C4, relay 312 operates in series with the cut-off winding of the called lineswitch and closes a locking circuit for 80 its lower winding at armature 352 including a branch of the locking conductor 314. At armature 354, relay 313 prepares a new locking circuit for relay 305; at armature 353 it prepares a circuit for pick-up relay 308; 85 at armature 350 it opens a point in the previously traced circuit of busy relay 310 so as to prevent this relay from operating over a similar circuit when the last digit is dialed; at armature 351, it places a ground potential 90 on test wiper 358 independent of the ground potential previously placed on this wiper through the test winding of the relay; at armature 355 it connects the operating magnet 373 of the code selector CS4 to 95 the operating conductor, at the same time disconnecting rotary magnet 360; and at armatures 349 and 356 it connects up the wipers 357 and 359.

When the next and last digit, the code selecting digit 5, is dialed, line relay 306 falls back five times, and shunts relay 307 with relay 311 five times, thereby transmitting five impulses of current over conductor 313 to operating magnet 373 of the code selector 100 CS4. Magnet 373 responds to the five impulses of current and advances the wiper 374 into engagement with the fifth associated bank contact. Relay 311 is energized throughout this series of impulses also, and, when it falls back at the end of the series, it closes at armature 348 a circuit for busy relay 310 through off-normal contacts 372 of the code selector CS4. Relay 310 operates at 105 this time and, in effect, locks itself energized at armature 344 by closing a shunt around relay 311 including armature 348, normal. It will be noted that the busy tone circuit is not closed at this time owing to the fact that armature 356 of switching relay 312 is operated.

The connection has now been extended to the desired line and the code selector CS4 has been set on the ringing-code conductor corresponding to the code necessary to signal the subscriber at the called substation. In order to insure that the ringing of the called subscriber will begin only at the beginning of a code, the pick-up relay 308 has been provided to close the circuit of the ringing 115 120 125 130

relay 309 only after a pick-up impulse has been received over pick-up conductor 376 and through the operated armatures 343 and 353. The code generating device shown in Fig. 4 grounds the pick-up conductor and the ringing-code conductors at the proper time as will be explained hereinafter. At this point it will suffice to say that a pick-up impulse is shortly received over impulse conductor 376, whereupon pick-up relay 308 operates and locks itself to conductor 314 at armature 337, at the same time opening its initial energizing circuit. At armature 338, relay 308 completes a connection from ringing relay 309 to the wiper 374 through armature 327. Accordingly, ringing relay 309 operates each time an impulse is placed on ringing code conductor 5, in a manner to be subsequently explained. Each time it operates, it places ground on the lower wiper 359 and it places ringing current on the upper wiper 357, operating the bridged ringers at the party-line substations. The ringing code sent out is, of course, that of the substation T2 and the subscribers at the other substation do not respond.

When the subscriber at substation T2 responds to the ringing of his bell by removing his receiver, a circuit is closed through the two coils of the ringer in parallel for the supervisory relay 304. This circuit, it will be noted, includes wipers 357 and 359, armatures 349 and 356, armatures 339 and 340, and the right-hand repeating-coil windings. Relay 304 operates when its circuit is closed and closes at armature 322 a circuit for reoperating relay 305. Relay 305 closes a locking circuit for itself at armature 326 including armature 354; it disconnects ringing relay 309 at armature 327; and at armature 329 it removes ground from the starting conductor 375.

It will be noted that the resistance 324 is inserted into the circuit of line relay 306 at armature 323 of relay 304. This operation is of no particular utility at this time, but is performed in order to give a calling operator supervision in case the connection is set up through an operator's switchboard, as will be explained hereinafter.

The two subscribers may now converse with each other, the heavy lines being used to outline the talking circuit. It is understood, of course, that a local source of talking current supply is used in both cases.

Release of connection from T1 to T2

When the conversation is terminated, the two subscribers replace their receivers. When the receiver is replaced at the substation T2, relay 304 falls back and opens the initial circuit of relay 305 at armature 322, leaving relay 305 operated through its locking circuit, and at armature 323 it shunts the resistance 324 so as to give the calling operator dis-

connect supervision in case an operator is handling the connection.

When the subscriber at substation T1 hangs up his receiver, relay 201 of the repeater R1 falls back and opens at armature 204 the circuit of relay 306 of the connector C4. Relay 306 falls back and shunts relay 307 with series relay 311, but relay 311 does not operate at this time because it is shunted in turn through armature 348, normal, and armature 344. At this time, the circuit of release relay 307 includes armature 334, operated, armature 328, and the vertical magnet 325. As a result, vertical magnet 325 operates when the release relay 307 is shunted, but the shaft and wipers are not disturbed due to the usual mechanical construction of the switch which prevents further elevation of the shaft and wipers after they have been rotated. Shortly after it is shunted relay 307 falls back and opens the circuit of vertical magnet 325 at armature 334, at the same time closing a circuit through off-normal contacts 336 for release magnet 330 and a branch circuit through the armature 341 for release magnet 371 of the code selector. Release magnets 330 and 371 now operate to start the restoration of their respective switches to their normal positions. In addition, relay 307 removes ground from release trunk conductor 302 at armature 332 and at armature 333 it removes ground from the locking conductor 314. Responsive to the removal of ground from release trunk conductor 302 the selector S4, Fig. 2, releases in the usual manner. When ground is removed from the locking conductor 314, relays 308 and 312 fall back. The falling back of relay 312 is retarded slightly by the copper on its armature end. When relay 312 falls back it replaces the ground potential on conductor 302 after a sufficient time has elapsed to permit the release of the selector S4, Fig. 2, to be started by the falling back of the switching relay (not shown) of the selector. The circuit path through which the ground potential is replaced includes armature 348, normal, off-normal contacts 372 of the code switch, armature 350, normally closed contacts controlled by armature 347, and armature 342. This path between ground and the release trunk conductor 302 is established so as to render the connector and the code switch busy while they are releasing.

Assuming that the code selector CS4 reaches its normal position before the connector C4 reaches its normal position, as will usually be the case, the circuit of relay 310 and the path through which ground is supplied to release trunk conductor 302 is opened at off-normal contacts 372 when the code selector reaches its normal position. Relay 310 thereupon falls back and opens the circuit of magnet 371 at armature 341, and at armature 344 removes the shunt from

around the winding of series relay 311, whereupon relay 311 operates in series with release magnet 330 and at armature 348 applies ground to release trunk conductor 302 through armature 326, normal. This second guarding circuit is established to guard the connector from seizure during its release.

When the shaft of the connector C4 reaches its normal position, off-normal contacts 335 and 336 open, and off-normal contacts 321 close. The circuit of the release magnet and the series relay is opened at springs 336, and the circuit of relay 305 including conductor 302, now grounded by series relay 311, is reestablished, and relay 305 operates. Relay 311, however, falls back an instant later and removes ground from conductor 302, rendering the connector idle again and releasing relay 305.

In the repeater R1, Fig. 2, when line relay 201 falls back, as above-mentioned, it opens the circuit of the release relay 202 and places the said relay 202 in a closed circuit with the result that relay 202 falls back after a slight interval, removing ground from release trunk conductor 157 and opening the circuit of relay 203. The switching relay 135 of the selector S1 and the magnet of the line-switch LS1 both deenergize, and relay 135 at armature 150 closes a circuit for release magnet 146 at armature 150 and through armature 144 and off-normal contacts 143. This circuit includes series relay 133. Relay 133 and magnet 146 both operate, and relay 133 closes a circuit for stepping relay 134 through the rotary-magnet interrupter contacts and off-normal contacts 141. Relay 134 now operates and applies ground potential again to release trunk conductor 125 so as to prevent the master switch from again stopping opposite this selector until it is fully released. When the normal position is reached, the release magnet and series relay circuit is opened at contacts 143; and the circuit of relay 134 is opened at contacts 141. Relay 134 thereupon falls back and removes ground from the release trunk conductor, and relay 133 falls back shortly thereafter.

All trunks busy at selector S1

Consider now the case when the selector S1 is operated, but is unable to find an idle trunk. The rotary movement takes place in the hereinbefore described manner and continues until the wipers 153-155 pass off the last bank contact upon the eleventh rotary set. When this occurs, springs 136 and 142 are operated by the usual cam arrangement. The circuit of relay 135 is opened at springs 142 to prevent this relay from operating at this time. At spring 136, the common busy tone lead is connected to the lower talking conductor 126, so as to give the calling subscriber a busy tone. Upon hearing this tone,

the calling subscriber is expected to hang up his receiver and bring about the release of the connection.

Operation of code-generating device

The operation of the code generating device, shown in Fig. 4, will now be considered. The relays 403 and 404 may be designated as the prime-mover relays because they generate the impulses to operate the other relays. The remaining relays, especially relays 405-410, operate to count the impulses generated by relays 403 and 404, and the device as a whole is capable of assuming any one of nineteen positions, successively, the operation being repeated in cycles. The positions of the device in which the various relays are operated have been noted on the drawings. Also, the positions of the device in which the principal conductors are grounded have been noted in order that the disclosure may be understood better.

When start conductor 375 is grounded, ground is extended through the lower armature of relay 402 to conductor 416, closing a circuit for relays 403 and 404, in series, through the resistance element 422. Relay 404 being short circuited, relay 403 is the only one that responds immediately. When relay 403 operates, it places ground on conductor 417 at its upper armature, and removes the shunt from around relay 404 at its lower armature. Relay 404 operates and prepares to place ground on conductor 419, and at the same time shunts relay 403. Relay 403 falls back, and the device may be said to be in its second position. In the second position of the device, a circuit is closed through the upper armatures of relays 403 and 404 for the upper winding of relay 406, including conductor 419 and the upper armature, normal, of relay 406. Relay 405 operates and closes a locking circuit for itself at its upper armature including the upper winding of relay 405, the lower armature of the said relay, and the grounded conductor 416.

With the device in position two, relay 404 is short circuited at the lower armature of relay 403, and relay 404 shortly falls back, the device thereupon passing into position three. When relay 404 falls back, it removes ground from conductor 419, whereupon relay 405 operates in the locking circuit of relay 406, and at its upper armature prepares a circuit for shunting relay 406. It will be noted now that a new locking circuit is completed for relays 405 and 406 in series, and that the circuit of the upper windings of these relays is opened. The new circuit includes the lower windings of the relays in series and the inner lower armatures of the two relays.

When relay 404 falls back it removes the shunt from around relay 403 with the result that relay 403 operates again and removes the shunt from around relay 404. Relay 404

now reoperates and shunts relay 403. This operation of relays 403 and 404 continues, in the manner described, until it is terminated by the action of relay 402, as will be described hereinafter.

It will be noted, that relay 403 is labeled "1, 3, 5, etc." while relay 404 is labeled "1-2, 3-4, etc." These labels indicate that relay 403 is operated in positions 1, 3, 5, etc., and that relay 404 is operated in positions 1 and 2, is released momentarily, is operated again in positions 3 and 4, etc.

With the device in position 4, ground is again placed on conductor 419, short circuiting lower winding of relay 406. Relay 406 falls back when this takes place and opens the previously established locking circuit at its inner lower armature. Relay 405 remains operated over conductor 419.

When the device arrives in position 5, ground is removed from conductor 419, whereupon, relay 405 falls back.

The above described operation of relays 405 and 406 is repeated, beginning with position 6.

While relay 406 is operated in positions 2 and 3, ground from conductor 416 is held on impulse conductor 420, extending to the similar relays 407 and 408. The result is an operation of relays 407 and 408 similar to the above described operation of relays 405 and 406, but the time required for a complete operation is twice as long as that of relays 405 and 406, on account of the fact that only half as many impulses are delivered over conductor 420 as are delivered over conductor 419. It may be seen, therefore, that relay 408 is operated in positions 2-5, 10-13, and 18, and that relay 407 is operated in positions 4-7, and 12-15.

It will be noted, that ground from conductor 416 is placed on conductor 421 as long as relay 407 is operated. The result is that conductor 421 is grounded in the positions of the device in which relay 407 is operated, conductor 421 being the impulse conductor extending to the third pair of counting relays 409 and 410. It may be seen, therefore, that relay 410 is operated in positions 4-11, and 50 that relay 409 is operated in positions 8-15.

When 418 is grounded in position 2, a circuit is closed through the lower armature of relay 412 for relay 413. Relay 413 operates and locks itself through the middle lower armature of relay 412 to conductor 416, and remains operated until relay 412 operates in position 13, as will be pointed out herein-after.

When the device arrives in position 6, relay 414 is operated from the grounded conductor 416 through the inner lower armature of relay 407, lower armature of relay 406, and the lower armature of relay 413. Relay 414 operates and locks itself through the locking conductor of relay 413, with the result

that relay 414 remains operated until ground is removed from this locking conductor at the beginning of position 13 when relay 412 operates.

When the device arrives in position 12, a circuit for relays 411 and 401 in series is completed from conductor 416 through the inner lower armature of relay 405, inner lower armature, normal, of relay 406, middle upper armature of relay 408, and the middle upper armature of relay 409. At its lower armature relay 411 locks itself and relay 401 to conductor 416. Relay 401 prepares a locking circuit for relay 402 at its inner armature.

When the device arrives in position 13, relay 405 falls back and closes at its lower armature a circuit through the inner upper armature of relay 411 for relay 412. Relay 412 operates and locks itself to conductor 416 until conductor 416 is ungrounded in position 18. At its middle lower armature, relay 412 opens the locking circuit of relays 413 and 414, whereupon these relays fall back.

When the device arrives in position 18, relay 408 is operated again, and it completes at its upper armature a circuit for relay 402 including the upper armature of relay 412 and the middle lower armature of relay 409. Relay 402, thereupon operates and locks itself to conductor 375 through the inner armature of relay 401, at the same time opening its initial circuit. At its lower armature, relay 402 removes ground from conductor 416 and places ground on pick-up conductor 376. The removal of ground from conductor 416 stops the operation of relays 403 and 404 and permits the operated relay 404 to fall back, and it opens the locking circuits of the relays 405-414, permitting such of these relays as are operated to fall back. Relay 401, which is in series with relay 411, is slow-acting and does not fall back right away when its circuit is opened upon the removal of ground from conductor 416.

When relay 401 falls back it opens the locking circuit of relay 402, the device is in position 19. A moment later relay 402 falls back and removes ground from pick-up conductor 376, reapplying it to conductor 416; then the device is in position 1 again.

The above described operation is repeated over and over as long as the ground potential remains on start conductor 375.

Considering now how the codes are placed on the various conductors, the conductor extending to terminal 1 is grounded through the lower armatures of relays 401 and 408 while the device is in positions 2-5; this code corresponds to one long ring.

The conductor extending to terminal 2 is grounded through the upper armatures of relays 403 and 411, and the middle armature of relay 410 while the device is in positions 1 and 3; this code corresponds to two short rings.

5 The conductor extending to terminal 3 is grounded in positions 3, 5, and 7 of the device through the upper armatures of relays 411, 413, and 409; this code corresponds to three short rings.

10 5 The conductor extending to terminal 4 is connected to the impulse conductor 417 through the upper armature of relay 411 and the middle upper armature of relay 410, and is grounded in positions 5, 7, 9, and 11; this code corresponds to four short rings.

15 15 In a similar way, the remaining code conductors are grounded in the positions indicated. The code placed on the conductor extending to terminal 5 corresponds to five short rings; the code placed on conductor 6 corresponds to two long rings; the code placed on conductor 7 corresponds to three long rings; the code placed on conductor 8 corresponds to a short ring and a long ring; the code placed on conductor 9 corresponds to a short ring and two long rings; and the code placed on conductor 10 corresponds to two short rings and two long rings.

20 25 *Call from substation T1 to substation T4*

It will now be assumed that the subscriber at substation T1, Fig. 1, desires to converse with the subscriber at substation T4, Fig. 7. 20 In order to complete the connection, the subscriber at substation T1 dials the number assigned to the manual exchange C (the digit 4). It will be assumed, that when the subscriber removes his receiver the lineswitch 25 LS1 seizes the selector S1, and that when the digit 4 is dialed the selector S1, upon raising its wipers to the fourth level, rotates them and finds the trunk line comprising conductors 159—161, extending to the trunk circuit TC1, as the first idle trunk line. When this occurs, line relay 223 of the trunk circuit TC1 operates over the calling line and places ground on the release trunk conductor 160 at armature 229, so as to maintain the 40 selector S1 and the lineswitch LS1 operated. At armatures 228 and 232 relay 223 disconnects the conductors of the trunk line TL1 from the corresponding conductors leading to the selector S2, Fig. 8, and connects them 45 instead to the associated right-hand repeating coil windings through the armatures 226 and 227, and at armature 231 it completes a connection including armature 225 between the ringing relay 222 and the 1² ringing code conductor of the code generating device in exchange A. The code placed on this conductor corresponds to one long ring, and it is, of course, repeated at intervals. At armature 230, ground is placed on conductor 375² 50 through armature 224 so as to start the associated code-generating device.

55 Each time ground is placed on the ringing-code conductor connected to terminal 1², ringing relay 222 operates and projects ringing current out over the trunk line TL1.

This ringing current passes through the left-hand windings of the repeating coil associated with the trunk circuit TC3, Fig. 5, to the upper winding of the ring-up relay 501. Relay 501 responds and closes a locking circuit for itself through its lower winding at armature 506, including armature 514 of sleeve relay 505. At armature 507, relay 501 closes a circuit for the line lamp 515.

70 75 When the operator notes the lighted condition of the lamp 515, she inserts the answering plug of an idle cord circuit, such as the cord circuit CC, into the jack J2. When the plug has been fully inserted, a circuit is closed from the exchange battery through the two left-hand windings of the cord circuit CC for the relay 504 in the trunk circuit TC3 including the right-hand windings of the repeating coil in the trunk circuit TC3, and armatures 508 and 510. At armature 80 85 511, relay 504 places ground on the lower terminal of the sleeve relay 505, whereupon sleeve relay 505 operates over the sleeve conductor of the left-hand plug of the cord circuit and closes a locking circuit for itself at 90 armature 514, at the same time opening the locking circuit of relay 501. Relay 501 falls back and extinguishes the lamp 515. At armature 512, relay 505 shunts the condenser in the left-hand windings of the repeating coil so as to improve the talking conditions, and at armature 513, it connects ground through relay 502 to both inner terminals of the left-hand repeating coil windings, thereby closing a circuit over the two conductors of the trunk line TL1, and the right-hand windings of the repeating coil at the trunk circuit TC1 for relay 221. Relay 221 operates over this circuit and closes a locking circuit for itself at armature 224, at the same time removing ground from conductor 375² 95 and disconnecting the code conductor 1² from the ringing relay 222. The closure of the locking circuit for relay 221 shunts the 100 current away from supervisory relay 502 in the trunk circuit TC3, permitting this relay 105 to remain non-operated.

110 115 In the cord circuit CC, supervisory relay 516 operates in series with relay 504 of TC3, and shunts the associated supervisory lamp so as to keep it from lighting in the sleeve circuit.

120 125 The operator now throws her key K2 into listening position and converses with the calling subscriber. Upon learning that the calling subscriber desires connection with the subscriber at substation T4, Fig. 7, the operator makes a note of the number of the calling substation and the number of the called substation. She then inserts the right-hand plug of the cord circuit CC into the jack of an idle trunk line, such as the trunk line TL4, extending to exchange D. When the plug is inserted to the jack J3, a circuit is 130

closed for relay 604 through the left-hand windings of the repeating coil in the trunk circuit and at armature 608 and 610. Relay 604 operates and grounds the lower terminal of relay 605, whereupon relay 605 operates over the sleeve circuit and closes a locking circuit for itself at armature 614. At armature 612, relay 605 shunts the condenser associated with the right-hand repeating coil 10 windings of the trunk circuit, and at armature 613 it connects ground to the two inner terminals of the associated right-hand repeating coil windings, closing a circuit including relay 602, the two conductors of the trunk line TL4 in multiple, and the line relay of the lineswitch LS3. Relay 602 operates in this circuit and opens the circuit of relay 604 at armature 608. Relay 504 falls back and relay 517 of the cord circuit CC remains non-operated, permitting the associated supervisory lamp to become lighted in the sleeve circuit.

The lineswitch LS3 now operates and extends the connection to the connector C5. 25 Line relay 803 of the connector C5, now operates over conductors 616 and 618 in multiple and closes a circuit for release relay 804. The circuit of release relay 804 includes, at this time, the normally closed contacts controlled by armatures 819 and 857, and rotary magnet 855. Relay 804 upon operating, locks itself to the operating conductor 822 at armature 826; grounds the locking conductor 701 at armature 825; and at armature 824 places ground on release trunk conductor 617 to maintain the connector busy to the lineswitches having access to it, and to hold the lineswitch LS3 operated. When ground is placed on conductor 617, relay 802 operates 40 through off-normal contacts 812 and prepares a locking circuit for itself at armature 817. At armature 819 it substitutes vertical magnet 816 for rotary magnet 855.

After inserting the right-hand plug of the 45 cord circuit CC into the jack J3, the operator inserts the plug of the dial cord DC into the dial jack DJ2. When the operator turns the calling device CD, in accordance with the first digit 3 in the number of the called substation, the off-normal springs of the calling device CD close a circuit for relay 603, whereupon relay 603 opens at armature 610 a further point in the circuit of supervisory relay 604, and at armature 609 it disconnects 50 relay 602 and substitutes the impulse springs of the calling device CD. Upon the return of the dial to its normal position, three interruptions are produced in the circuit of line relay 803, Fig. 7, and when the normal position is reached, the off-normal springs bring about the deenergization of relay 603, whereupon relay 602 is brought into the circuit again.

Each time line relay 803 of the connector 65 C5 falls back it shunts release relay 804,

thereby operating vertical magnet 816 three times. Series relay 809, included in the shunt circuit around relay 804, operates upon the first impulse and, being slow-acting, remains operated throughout the series of impulses. At armature 843, relay 809 completes the locking circuit of relay 802 so as to maintain the relay operated after its initial circuit is opened at off-normal contacts 812.

At the end of the vertical movement of the 75 connector, relay 809 falls back and permits relay 802 to deenergize and transfer the operating conductor 822 to the rotary magnet 855.

When the calling operator dials the next 80 digit 0, line relay 803 falls back and operates rotary magnet 855 ten times. Relay 809 is again operated throughout the series of impulses and it closes at armature 842 a circuit for relay 810. Relay 810 operates and at 85 armature 845 connects test wiper 857 to busy relay 808 through the normally-closed off-normal contacts of the code selector CS5. In case the called line is busy, relay 808 is operated at the end of the rotary movement, when 90 the wipers 856—859 are on the contacts of the called line, and the busy tone is transmitted back to the operator at armature 841, in the usual manner. If the line is idle, a circuit for the upper winding of the switching relay 95 811 is completed upon the falling back of relays 809 and 810, which circuit includes the grounded release trunk conductor 617, armature 836, upper winding of relay 811, armature 845, armature 847, test wiper 857, test 100 contact of the called line, and the bridge-cut-off winding (not shown) of the lineswitch LS4. Relay 811, upon operating, locks itself to conductor 701 at armature 848; at armature 847 shifts the test wiper 857 from 105 the upper winding of relay 811 to ground; connects up the wipers and opens a point in the busy signalling circuit at armatures 846 and 853; shifts the operating circuit to the operating magnet of the code selector at armature 851; and at armature 850 prepares a circuit for pick-up relay 805.

When the calling operator dials the next 110 and last digit 5, five impulses of current are transmitted to the operating magnet of the code selector, whereupon the wiper of the code selector is driven into engagement with the fifth associated bank contact. Relays 809 and 810 are energized throughout this digit, and the circuit of relay 808 is maintained open at armature 845. When relay 809 falls back, a circuit is closed at armature 842 through the normally-open off-normal contacts of the switch CS5 and for the busy relay 808. Relay 808 operates at this time 115 and, at armature 837, shunts the series relay 809 so as to prevent any further operation of this relay; at armature 839, it shifts the operating conductor back to vertical magnet 816; it prepares the release circuit at armature 120 125 838.

835; and at armature 838 it completes the connection between the pick-up conductor and pick-up relay 805. The start conductor 375' having been grounded through contacts 823 and armature 820, the associated code generating device is operating, and, when the pick-up conductor is grounded, pick-up relay 805 operates and locks itself to conductor 701. At armature 829, it completes 10 a connection through armature 818 between ringing relay 806 and the wiper of the code selector. The ringing current is now projected out over the called line by relay 806 in accordance with the code of the substation 15 T4.

When the subscriber at substation T4 responds a circuit is closed over the two sides of the called line in parallel for relay 801. At armature 813, relay 801 closes a circuit for 20 relay 802. Relay 802 operates and at armature 817 closes a locking circuit for itself including armature 849; it disconnects the ringing relay at armature 818; and at armature 820 it removes ground from start conductor 375'. Relay 801, at armature 814, inserts the resistance 815 into the circuit of line relay 803, whereupon the marginal supervisory relay 602, Fig. 6, falls back and again completes a circuit through relay 604, 30 whereupon the right-hand supervisory relay 517 of the cord circuit CC operates and extinguishes the associated supervisory lamp so as to give the operator answered supervision.

35 The two subscribers may now converse with each other in any desired manner, and when the conversation is terminated they both replace their receivers.

When the receiver is replaced at the calling substation, line relay 223 of the trunk circuit TC1, Fig. 2, falls back and removes ground at armature 229 from release trunk conductor 160, permitting the line-switch and selector, Fig. 1, to release. At armatures 45 228 and 232 the conductors of the trunk line TL1 are switched back to the selector S2, and at armature 230 the locking circuit of relay 221 is opened, whereupon relay 221 falls back.

The supervisory relay 502, Fig. 5, now operates over the trunk line TL1 in series with the line relay (not shown) of the selector S2, and at armature 508 opens the circuit of supervisory relay 516, whereupon supervisory relay 516 falls back and permits the associated lamp to become lighted as a disconnect signal.

50 The selector S2, see Fig. 8, is incidentally prepared for operation when its line relay operates over the trunk line in series with the supervisory relay 502, Fig. 5,

When the receiver is replaced at the called substation, relay 801 falls back and at armature 814 shunts the resistance 815, whereupon relay 602, Fig. 6, operates again over the 55 trunk line TL4 and gives the operator a fur-

ther disconnect signal by opening the circuit of supervisory relay 517 at armature 608.

Upon perceiving the two disconnect signals, the operator pulls down the connection. When the plug is removed from the jack J2, 70 the associated supervisory lamp becomes extinguished, and sleeve relay 505 falls back. At armature 513, the simplex circuit over the trunk line TL1 is opened, whereupon the line relay of the selector S2 falls back and 75 causes the restoration of the selector to its normal condition.

When the plug is removed from the jack J3, sleeve relay 605 falls back and removes ground from the inner terminals of the associated right-hand repeating coil windings, whereupon line relay 803 of the connector C5 falls back and shunts release relay 804, causing an incidental operation of vertical magnet 816. After a slight interval, relay 804 85 falls back and, at armature 824, removes ground from conductor 617 so as to permit the lineswitch LS3 to release. At armature 825 it removes ground from conductor 701, permitting relays 805 and 811 to fall back. 90 The relay 811 releases the bridge-cut-off winding of the lineswitch LS4 at armature 847, and at armature 849 opens the locking circuit of relay 802, whereupon relay 802 falls back. Release magnet 821 operates 95 through off-normal contacts 827, and the release magnet of the code selector operates through off-normal contacts 835. It is to be noted, that no reapplication of ground application of ground potential to conductor 617 100 occurs at this time, as it is not desired to busy the connector C5 during the release. When the code selector CS5 reaches its normal position, the circuit of relay 808 is opened, and relay 808 falls back, opening the release magnet circuit of the code selector at armature 105 835. At armature 837, relay 808 removes the shunt from around the winding of relay 809, whereupon relays 809 and 810 operate again. However, the reapplication of ground to the 110 release trunk conductor, described in connection with the similar relay 311 of the connector C4, does not occur at this time, owing to the elimination of the connection at armature 817 corresponding to the connection between the resting contact of armature 326, Fig. 3, and the release trunk conductor 302. When the connector C5 reaches its normal position, the circuit of magnet 821 and relay 809 is opened at off-normal contacts 827. Relay 809 now falls back and opens the circuit of relay 810 at armature 842, with the result that relay 810 falls back also.

The entire connection is now released, and the apparatus involved therein may be used 115 in setting up other connections.

Regarding the reason for the elimination of the busy-during-release feature from the connector C5, it may be pointed out that, in case the connector C5 or the code selector CS5 120

should become mechanically defective so that no release would occur, the ground potential would remain applied to conductor 617, with the result that, in case the lineswitch used to make the original call should be reoperated right away to make a new call before the master switch has "picked-up" the lineswitch and carried it to an idle trunk, the lineswitch would reoperate and seize the defective trunk line, and become locked in connection therewith, until the trouble was cleared. Now, the exchange C is a small exchange, and is unattended, for the most part, and it is thought that the danger of lines becoming thus locked up out of commission more than offsets the gain due to the prevention of the seizure of the switches while they are releasing. On the other hand, the busy-during-release feature has been applied to the connector C4, Fig. 3, because this connector is preceded by a selector and as soon as the release starts the selector is freed and there is no danger of a line being locked out of commission upon the reapplication of the ground potential to the release trunk. However, notwithstanding the danger of lines being locked out of commission, the guard-during-release feature has been applied to the selector S1, as it is assumed that an attendant is present most of the time in exchange A, and that he will be ready to take care of such situations as they occur. The same applies to exchange B.

Call from substation T4 to substation T3

In order that the automatic rotary operation of the connector C5, Fig. 7, be understood, this operation will be explained in connection with a call from the subscriber at substation T4 in exchange D, to the subscriber at substation T3 in exchange C.

It will be assumed that, when the subscriber at substation T4 removes his receiver, the lineswitch LS4, Fig. 8, seizes the connector C5 at a multiple of the conductor 616-618, see Figs. 6 and 7. When this occurs, the connector C5 is prepared for operation in the manner hereinbefore explained, and a holding circuit for the calling lineswitch is closed over conductor 617.

The calling subscriber now dials the number 211 assigned to the exchange C for the use of subscribers in exchange D. When the digit 2 is dialed, the connector C5 responds by raising its wipers opposite the second level of bank contacts.

When the second digit, the digit 1, is dialed, the wipers of the connector C5 are rotated one step in the hereinbefore described manner. It will be recalled that the series relay 809 is operated in series with the operating conductor 822 when the rotary movement of the connector takes place, and that relay 810 is operated by relay 809 at armature 842. The operation taking place at the end of the

directed rotary movement of the connector, depends upon whether the trunk line TL4 is busy or idle, it being assumed that the trunk TL4 is the one terminating in the first set of bank contacts in the second level. Assuming that the trunk line is busy, there is a ground potential on the test contact thereof, now encountered by test wiper 857, and a circuit is therefore closed through armatures 847 and 845, and off-normal contacts of the code selector CS5 for busy relay 808. Busy relay 808, at armature 840, prepares a circuit for stepping relay 807, including the rotary test wiper 858. When series relay 809 falls back and opens the circuit of the slow-acting relay 810 at armature 842, it completes at armature 844 a connection between relay 807 and the test wiper 858, this connection including the interrupter contacts 854 and armature 852. Relay 807 now operates from the ground potential on the test conductor of the trunk line, which ground potential is carried to the rotary test contact through the associated jumper connection. Upon operating, relay 807, at armature 833, closes a holding circuit for slow-acting relay 810, so as to prevent it from falling back at this time. At armature 834, relay 807 locks itself to the release trunk conductor 617 by placing ground therefrom on the test wiper 858, and at armature 832 it closes a circuit over the operating conductor 822 for rotary magnet 855. Rotary magnet 855 now responds and advances the wipers another step. Near the end of its stroke, magnet 855 opens the circuit of relay 807 at contacts 854, whereupon relay 807 falls back and opens the rotary magnet circuit, resulting in the deenergization of the rotary magnet. If the test contact of the second trunk line is busy, the stepping relay operates again and the rotary movement continues. When an idle trunk line is reached, relay 807 ceases to operate and the busy relay 808 falls back. As an alternative, the wipers may be driven to the last trunk line of the group, and, if this trunk line is busy, the busy relay remains operated, but no further operation of the stepping relay 807 takes place on account of the omission of the corresponding jumper connection between the regular test contact and the rotary test contact of the last trunk line. The busy signal is transmitted back in the latter instance, and the calling subscriber replaces his receiver, bringing about the release of the connection.

For the purpose of the present description it will be assumed that the trunk line TL4 is idle when tested, with the result that relay 807 does not operate, and busy relay 808 remains normal when the directed rotary movement is completed.

Responsive to the deenergization of relay 810, which takes place when its circuit is opened by relay 809, the switching relay 811 operates in series with the bridge-cut-off

winding of the lineswitch LS3, connecting up the wipers of the switch and extending the operating conductor to the operating magnet of the code switch DS5.

The calling subscriber now dials the code digit 1 so as to cause ringing current to be applied over the trunk line, as it is in the hereinbefore described manner after the code switch has been set on the first bank contact.

10 When the ringing current is projected over the trunk line TL4, the ringing response relay 601 in the trunk circuit TC5 operates and closes a locking circuit for itself at armature 606, at the same time closing a circuit for the call lamp 615.

15 When the operator notes the lighted condition of the lamp 615, she inserts the answering plug of an idle cord circuit, for example the left-hand plug of the cord circuit CC, into the jack J3. Relay 604 operates over tip and ring conductors of the plug and jack and connects up the sleeve relay 605 at armature 611, whereupon the sleeve relay operates and closes a locking circuit for itself, at the same time releasing relay 601 and connecting up the marginal supervisory relay 602 in a simplex circuit with the conductors of the trunk line TL4.

20 The answering relay 801 of the connector C5 operates over this circuit so as to cause the ring-cut-off relay 802 to operate and lock energized.

25 The marginal supervisory relay 602 in the trunk circuit TC5 does not operate at this time, however, owing to the relatively high resistance of relay 801 in the connector C5. Since relay 602 does not operate, the circuit of relay 604 remains closed and the supervisory relay 516 of the answering end of the 30 cord circuit operates to prevent the lighting of the associated supervisory lamp.

35 After throwing her listening key and ascertaining the number of the called lines, the operator inserts the calling plug, the right-hand plug, of the cord circuit CC into the multiple jack of the called line, after which she applies ringing current by throwing the key K2 into ringing position. The calling supervisory lamp operates through the sleeve 40 circuit when the connection is made with the called line.

45 When the called subscriber responds, the supervisory relay 517 operates and extinguishes the associated supervisory lamp.

50 The two subscribers may now converse with each other. When the conversation is terminated, the two subscribers replace their receivers. The replacement of the receiver at the called substation results in the de- 55 energization of supervisory relay 517 and in the consequent lighting of the associated lamp as a disconnect signal.

When the receiver is replaced at the calling substation T4, the connector C5 releases in 60 the manner hereinbefore described, where-

upon the lineswitch LS3 on the trunk line TL4 operates responsive to the opening of the circuit through its cut-off winding and seizes a connector similar to the connector C5. When this occurs, the marginal relay 602 in the trunk circuit TC5 operates, first in series with the line relay of the lineswitch LS3, and then in series with the line relay of the seized connector. At armature 608 relay 602 opens the circuit of the answering supervisory relay 516 of the cord circuit CC, whereupon this relay falls back and the associated lamp is lighted as a disconnect signal.

70 When the operator perceives that both supervisory lamps are lighted, she pulls down the connection. The connector seized by the last mentioned operation of the lineswitch LS3 is freed in the usual manner when the plug is removed from the jack J3.

Local call on the line of substation T1

80 Assuming now that the subscriber at substation T1 desires to converse with another subscriber on the same line, the removal of the receiver at substation T1 is followed by 85 the usual operation of the lineswitch LS1. It may be assumed for example that the selector S1 is the one seized by the lineswitch LS1. The usual holding and guarding circuit is closed over conductor 125 when release relay 132 operates.

90 After removing his receiver, the calling subscriber operates his hand generator 103 in accordance with the code assigned to the desired substation on the calling line. Upon 95 the first operation of the generator 103, relay 111 responds to the ringing current and closes a circuit through spring 120 of the lineswitch LS1 and its associated contacts for relay 112. This circuit includes the two coils of the 100 ringer 104 in parallel, conductors 101 and 102 in parallel, and the two windings of relay 111 in parallel. Upon operating, relay 112 closes a locking circuit for itself at its inner lower armature; disconnects the talking conductors from the lineswitch at its upper and lower armatures, and at its inner upper armature disconnects the private normal conductor 127 from the spring 119 and winding 115 and connects it to ground locally. The line and release relays of the selector S1 now falls back, whereupon the lineswitch LS1 releases. It will be noted that the generator 103 is normally short-circuited by its own contact, and that when it is operated the short circuit is removed and the generator is placed across the line. It will 110 be noted also that when the generator is operated the bridge including the secondary winding of the repeating coil and the receiver is opened. This prevents a large portion of the current from the generator from being shunted away from the line. It will be noted that there is a talking condenser in series 115 with the receiver circuit. This condenser is 120

125 When the receiver is replaced at the calling substation T4, the connector C5 releases in 130 the manner hereinbefore described, where-

provided to lessen the shunting effect on the ringing current in case the receiver is removed at some unwanted telephone while ringing current is passing over the party line, each telephone being so equipped.

5 When the subscribers both replace their receivers after the conversation is over, relay 112 falls back, restoring the associated circuit conditions to normal.

10 What is claimed is:

1. In a party line automatic telephone exchange system, automatic switching equipment provided in the central office common to a plurality of lines for setting up connections, 15 and means automatically operated when a subscriber on one line calls another subscriber on the same line for freeing all common central office switching equipment.

2. In a party line automatic telephone exchange system in which ringing-current generators are provided at the party-line substations, common switching devices at the exchange, means for rendering one of said devices temporarily individual to a calling line, 25 and means responsive to the operation of the hand generator at a calling telephone to signal another party on the same line for causing the seized switching device to be freed and for preventing any other device from being taken into use by said line until such line has been again cleared out.

3. In a party line telephone exchange system of the magneto type, a device at the central office responsive to the removal of the receiver on a party line, means at any one of the party line substations for applying ringing current to the line to signal other substations on the same line, and a lock-out device at the central office responsive to the 35 operation of the signalling device on a calling substation for terminating the response of the central office device and for preventing a further response until the line has again been cleared out.

4. In a party line telephone system, a lock-out device in the central office responsive to an application of ringing current to a calling party line by one of the substations thereon, and means for preventing the said lock-out device from operating responsive to an application of ringing current to the same line by the central office equipment when it is 50 a called line.

5. In a telephone system, a line terminating in an automatic exchange, means in said automatic exchange for setting up a connection including said line as a calling line and for setting up a connection including said line as a called line, circuit connections for 55 effecting a current flow over said line when the same is a calling line and for effecting a current flow over said line of a substantially reduced strength when the said line is a called line.

6. In a telephone system, a line terminat-

ing at an automatic exchange, switching mechanism in the automatic exchange for setting up connections including said line as a calling line and for setting up connections including said line as a called line, current supply circuits of a given resistance, other current supply circuits of a substantially higher resistance, and means whereby the former current supply circuits are connected with said line when it is set up in a connection 70 as a calling line and whereby the high resistance circuits are connected to said line when it is a called line.

7. In a telephone system, a trunk line extending between two exchanges, a supervisory control device in the second exchange, an answering relay in the first exchange operated over the trunk line when a call over the trunk line from the first exchange to the second exchange is answered at the second exchange, said supervisory control device being connected in a circuit in the second exchange over said trunk line with said answering relay in the first exchange, and means for maintaining said answering relay operated 75 independent of the continued answered state of the call in the second exchange and for preventing a response of the supervisory control device by closing a locking circuit for the answering relay in the first exchange, whereby the current flow through the answering relay is shunted away from said supervisory device.

8. In a telephone system, a two motion automatic switch for use in setting up telephone connections to lines accessible to said switch, a single wound combination change over relay and ring-cut-off relay in said switch, and means for operating said relay to effect a change over from one motion to the other motion of said switch, and for subsequently operating said relay to prevent further application of ringing current to a connected line after the switch has operated and applied ringing current to the line.

9. In a telephone system, a party line having two talking conductors, a substation on said line, a receiver circuit bridged across said conductors at said substation, means at the substation for applying signalling current for said conductors, means for automatically opening said bridge when the signalling current is applied, a dial at said substation, switching mechanism terminating said line, means in said switching mechanism effective to extend the line if digit impulses are transmitted and effective to release the switching mechanism if signalling current is transmitted.

10. In a party line telephone system, a party line terminating in a line switch, automatic switching mechanism accessible to the line switch, means responsive to the initiation of a call at any station on the line for bridging the receiver circuit across the line and for 125 130

causing the line switch to seize said switching mechanism, means at each station for transmitting digit impulses over the line to control the switching mechanism if a station on a different line is desired, signalling means 5 at each station for applying signalling current to the line if a station on the same line is desired, means in the line switch responsive to the signalling current for releasing the switching mechanism, and means at the calling station responsive to the operation of said signalling means for opening said bridge including the receiving circuit.

11. In a party line telephone system, a plurality of lines, two talking conductors and a plurality of stations for each line, means at each station for controlling the calling of any station on the same or on a different line, said means comprising means responsive to the removal of the receiver for bridging the telephone instrument across the talking conductors, means for applying signalling current to the line to signal a station on the same line and means for transmitting digit impulses 20 over the line to control the setting up of a connection to a different line, automatic switching mechanism at the central exchange, common to a plurality of lines and seized responsive to the removal of the receiver at a 25 calling station and controlled by digit impulses for extending the calling line towards other lines, means at the central station responsive to signalling current from the calling station for releasing said switch, and means at the calling station responsive to 30 the operation of the signalling means for opening the bridge including the telephone instrument across the talking conductors.

12. In a telephone system, a party line 40 extending to the exchange and there terminating in an automatic switch, a generator at a calling station on said line for ringing other stations on the same line, a bridge across said line at said switch, said bridge being low enough in resistance to prevent 45 effective ringing, means responsive to the removal of the receiver at the calling station for operating said switch, means responsive to such operation for opening said bridge, a 50 second bridge placed across the line at the calling station by the removal of the receiver, and means effective upon the operation of said generator for opening said second bridge.

13. In a telephone system, a two motion 55 automatic switch for use in establishing connections, a trunk comprising speaking conductors and a test conductor terminating in said switch, a single wound combination 60 change-over relay and ring-cut-off relay in said switch, means for operating said relay over the test conductor of the trunk responsive to the seizure of the switch thereover to effect a change-over from one motion to the 65 other motion of the switch, and means for

subsequently operating said relay to prevent further application of ringing current to a connected line after the switch has operated and applied ringing current to the line.

14. In a telephone system, a connector 70 switch and an auxiliary signal selecting switch associated therewith, means for directly operating said switches to extend a connection, means for restoring said switches to normal position, and separate guarding circuits for preventing the seizure of the connector switch effective respectively during the restoring operation of each switch.

15. In a telephone system, a connector 80 switch and an auxiliary switch associated therewith, means for directly operating said switches to extend a connection, means for restoring said switches to normal position, a guarding circuit effective during the restoring operation of said auxiliary switch 85 for preventing the seizure of the connector, and a second guarding circuit effective during the restoring operation of said connector switch and subsequent to the restoration of said auxiliary switch for preventing the seizure of the connector switch.

16. A two motion switch having primary and secondary magnets for controlling respectively the vertical and rotary motions of the switch, a release control relay in said switch, an auxiliary device including a stepping magnet operatively associated with said first switch, and means for energizing said relay in series respectively with the primary magnet during the vertical motion of the switch, with the secondary magnet during the rotary motion of the switch, and with the stepping magnet during the operation of said auxiliary device.

In witness whereof, I hereunto subscribe 105 my name this 7th day of December, A. D. 1926.

NORMAN H. SAUNDERS.
